UNITED STATES PATENT OFFICE.

LEON T. MART, OF KANSAS CITY, MISSOURI.

NONCLOGGING SPRAY NOZZLE.

Application filed August 21, 1926. Serial No. 130,647.

My invention relates to spray nozzles and more particularly to a non-clogging spray nozzle for cooling purposes.

It is a purpose of my invention to provide a nozzle for use in connection with spray ponds for cooling water in connection with power plants, that is so constructed that the same will not clog easily but will at the same time give a very uniform spraying action. In order to accomplish this, my improved nozzle is made with all the passages thereof as large as these can possibly be made and still obtain efficient spraying action. Furthermore in order to prevent clogging, the passages are made free and open without any projections into the same or any inserted parts to obtain the spraying action of the nozzle. In other words, the spraying action is obtained entirely due to the contour of the walls of the passages themselves, and the contour of these walls is smooth so as to avoid any narrow passages or protuberances into the interior of the nozzle that might collect foreign matter and clog the nozzle.

It is more particularly a purpose of my invention to provide a spray nozzle wherein the spraying action is obtained by setting up a whirling action of the water within the chamber of the nozzle by introducing the stream of water into the nozzle tangentially of the wall of said chamber and discharging the same from a wide orifice located in a dome shaped end portion of said chamber. The inlet into said chamber is preferably in the form of a narrow-mouth nozzle having walls that gradually converge toward the chamber, said walls being curved and being so formed that the entrance to the inlet passage to the chamber is substantially rectangular and is elongated in the direction of the axis of the chamber and has the one wall thereof substantially coincident with the side wall of the chamber so that the stream of liquid entering the chamber enters substantially tangentially of said wall. Furthermore the main body portion of the nozzle preferably comprises a substantially cylindrical chamber having a straight substantially plane end wall portion and having a dome shaped end opposite the plane end wall which is provided with a central orifice that is relatively wide. The dome shaped end is preferably spheroidal and the discharge orifice

has a substantially cylindrical wall portion of uniform diameter.

It is furthermore a purpose of my invention to provide a nozzle of the above mentioned character in which the cylindrical wall portion of the chamber extends a substantial distance beyond the nearest edge of the inlet opening toward the discharge orifice, which produces a much more efficient spraying action than would be the case if the dome shaped portion were closely adjacent said inlet opening, the elongated cylindrical swirl chamber producing a uniform spraying action with the wide mouthed orifice and making it unnecessary to provide any vanes, deflecting members, screens or other devices to obtain a good spraying action.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a perspective view of my improved nozzle.

Fig. 2 is a view partly in longitudinal section and partly in perspective of my improved nozzle, the section being taken substantially on the line 2—2 of Fig. 4.

Fig. 3 is a section taken at right angles to Fig. 2, being taken substantially on the line 3—3 of Fig. 4, and

Fig. 4 is a transverse sectional view taken at right angles to Figs. 2 and 3.

Referring in detail to the drawings:

My improved nozzle comprises the body portion 10 which is provided with a plane closed end wall floor 11 perpendicular to the axis of the body portion and a substantially cylindrical side wall portion 12 of uniform diameter, and a dome shaped end portion 13 which is substantially spheroidal in form and which terminates in a short neck portion 14 providing a discharge passage that has a substantially cylindrical inner face.

Extending from one side of the body portion 10 is an inlet 15 which is provided with a polygonal outer wall portion 16 whereby

a tool may be applied thereto for screwing the nozzle in place, said inlet being internally threaded as indicated at 17, whereby the nozzle may be threaded onto any desired pipe connection. The threaded end portion 17 is substantially circular in cross section and has a gradually reduced portion 18 leading toward the main body portion 10, said gradually reduced portion having the spirally 5 curved side wall portions 19 and 20 which lie substantially opposite each other, and the substantially straight parallel top and bottom wall portions 21 and 22 forming an inlet channel. The curved wall portions 19 and 20 are of such a shape as to gradually change the cross sectional shape of the opening in the member 15 from a substantially circular contour to a rectangular passage 23 where the inlet discharges into the chamber 10 24 provided in the main body portion 10. Moreover, the curvature of the wall portions 19 and 20 is substantially convex from the circular threaded portion 17 to the rectangular portion 23, gradually reducing the 15 cross sectional area of the passage so as to form a narrow-mouthed inlet into the chamber 24. The wall 22 lies in a plane parallel with the floor of the chamber and substantially flush with the wall 11, being only 20 slightly offset therefrom as at 25. The wall portion 21 lies substantially midway of the length of the nozzle, being substantially midway between the upper or outer face 26 of the discharge outlet 14 and the closed end 25 wall 11. The cylindrical portion of the chamber 24 which is of substantially uniform diameter, extends from the closed wall 11 a considerable distance past the edge of the opening 23 which is nearest the discharge 30 orifice in the portion 14 and merges into the substantially spheroidal dome shaped end portion 13 near the portion 14, the arcuate or dome-shaped inner wall portion being indicated by the numeral 27, the inner cylindrical side face portion by the numeral 28 and the inner cylindrical face of the orifice in the portion 14 by the numeral 29. Thus the smooth cylindrical wall portion 28 merges into the dome shaped portion 27 in a gradually curved wall portion, and the arcuate or dome shaped wall portion 27 merges with the cylindrical walled passage 29 of the neck 40 portion 14.

It will further be noted that the side edge 50 30 of the rectangular opening 22 coincides substantially with the cylindrical wall portion 28 there being a slightly flattened portion at 31 adjacent the portion 30. The stream of liquid passing through the opening 22 thus strikes the cylindrical wall portion 28 substantially on a tangent, causing the liquid to be thrown into a whirling motion with the center of the swirl substantially

on the axis of the cylindrical portion 28. This continues as the liquid travels around 55 the cylindrical wall portion 28 and toward the orifice in the portion 14 which orifice, it will be noted, is of large diameter, being of substantially half the diameter of the cylindrical portion 28. The travel of the liquid 60 around the dome shaped portion 27 and up through the discharge orifice causes the same to be discharged in a uniform spray of large area around said nozzle, the liquid thus being sprayed over a considerable area and being 65 finely divided to obtain an efficient spraying action. As all the passages are large and as there are no projecting parts in the chamber 70 24 upon which or around which foreign matter can collect, it will be substantially impossible to clog the nozzle, the nozzle freely permitting the passage of the liquid there-through, and due to the elongated cylindrical body portion thereof, spraying effectively in 75 spite of the large passages used throughout. The nozzle accordingly has a very large capacity and at the same time is highly reliable because of the fact that clogging is 80 substantially entirely eliminated.

What I claim and desire to secure by 90 Letters Patent is:

1. A spray nozzle comprising a body member forming a swirl chamber of substantially cylindrical cross section for the greater portion of its depth and terminating at one end 95 in a relatively shallow dome having a concentric outlet port and at the other end in a plane floor substantially perpendicular to the axis of the chamber, the body having a substantially rectangular inlet port elongated in 100 the direction of the axis of said chamber, and an inlet channel having parallel top and bottom walls, the inlet port being arranged to discharge tangentially to the wall of said chamber and of substantially less depth than 105 the chamber to provide an area of unrestricted relatively circular swirl intersecting the inlet and an area of unrestricted spiral swirl between the inlet and said dome.

2. A spray nozzle comprising a body forming a cylindrical chamber having a plane floor at one end perpendicular to the axis of the chamber, and terminating at the other end in a relatively shallow dome having a concentric outlet port, the body having a substantially rectangular inlet channel including a straight bottom wall located in a plane parallel with the chamber floor and a straight top wall parallel with the bottom wall and located intermediately of the cylindrical chamber, the inlet channel being arranged to discharge tangentially to the wall 115 of said chamber.

In testimony whereof I affix my signature.

LEON T. MART.
